UNITED STATES PATENT OFFICE

2,338,122

PRINTING TELEGRAPH APPARATUS

Berthel F. Madsen, Chicago, Ill., assignor to Teletype Corporation, Chicago, Ill., a corporation of Delaware

Original application April 20, 1938, Serial No. 203,021. Divided and this application June 14, 1941, Serial No. 398,081

12 Claims. (Cl. 197—71)

This invention relates to printing telegraph apparatus, and particularly to printing telegraph apparatus in which the characters are printed in page form from type elements carried upon the periphery of a rotatable and selectively arrestable type carrier.

This application is a division of copending application, Serial No. 203,021, filed April 20, 1938, by Berthel F. Madsen, which has matured into Patent No. 2,284,666, issued June 2, 1942.

An object of this invention resides in the provision, in a printing telegraph receiving unit embodying a selectively rotatable type wheel which is shiftable into and out of printing position to afford visibility, of instrumentalities for controlling shifting of the type wheel and for arresting it at various elevational positions relative to the printing level.

In Patent No. 2,296,874, granted September 29, 1942, to Albert H. Reiber, there is disclosed a type wheel printer with reference to which the present invention stands as an improvement. According to the disclosure of that application, the type wheel is slidably supported upon the type wheel shaft by a frame which may occupy either of two positions and may be shifted to either one or the other of the two positions under the control of the case shift mechanism for aligning either of two rows of type elements carried by the type wheel with the level at which printing is to be effected. When the type wheel has been shifted to a given position by the shifting of the supporting frame, it remains in that position until the case shift signal assigned to the shifting of the type wheel to its other position has been received and rendered effective.

According to the present invention, the type wheel is movable axially of the type wheel shaft and is supported by a shiftable frame, the normal position of the frame being such that the entire type wheel is held below the level at which printing is to be effected so that a line which is being printed, including the last character, shall be visible. For each cycle of operation of the receiving unit, the type wheel supporting frame is oscillated so as to bring the type wheel into printing position before the printing operation occurs and to restore it to normal position after the printing of a character has been accomplished. In the preferred embodiment of the invention, the type wheel supporting frame is moved by a cam to bring the type wheel into printing position before the printing operation and is restored to normal position under the

control of a cam. The amount of movement imparted to the type wheel in elevating it to printing position is controlled by a leverage mechanism which is in turn under control of the shift and unshift function mechanism of the receiving unit, so that the function mechanism, instead of shifting the type wheel to the desired position as in the disclosure in the hereinbefore mentioned copending application merely operates to determine the height to which the type wheel is to be elevated. The type wheel elevating mechanism includes a lost motion leverage assembly so that the type wheel may be arrested short of its uppermost position while permitting the elevating cam and part of the elevating mechanism to operate as though imparting full movement to the type wheel. This mechanism operating under control of the shift and unshift function mechanism prepares the leverage mechanism to shift the type wheel to either of its elevated positions when the actuating cam therefor operates the main portion of the leverage mechanism.

The disclosure of the afore-mentioned patent to A. H. Reiber reveals that the transfer operation, by which the code discs of a code disc selector are set in accordance with a new signal combination and the type wheel is released for rotation to a new position of arrestment corresponding to the transferred signal, is performed by a cam included in a cam assembly which also includes the cam for performing the printing operation. The printing operation is timed to precede the transfer, the reason for this being that the interval of time which it is desirable to allot to the rotation of the type wheel to a new position of arrestment might be longer than the interval of time between the transfer operation and the end of the cycle of the cam assembly which includes the transfer and printing cams, so that the printing operation would not be timed to be performed before the end of the cycle in which the transfer occurs. Consequently, the print operation is timed to occur substantially immediately after the beginning of the next cycle of operation of the cam assembly and the result is, as described in the copending application, that the printer comes to rest with a signal combination stored in the code disc selector mechanism which would not be cleared out until the next cycle of operation of the cam assembly. If the signal combination which is stored represents the last character of a message, it is necessary to introduce an idle operation of the printer 55 in order to print the character for the selection

of which the type wheel has been rotated in response to the signal combination stored in the code disc selector.

According to the present invention, as described in detail in the afore-mentioned patent to Berthel F. Madsen of which this application is a division, the cam which controls the printing operation has been removed from the cam assembly which includes the transfer cam and has according to one embodiment, been included in a separate cam assembly carried by a shaft separate from that which supports the transfer cam assembly, and according to another embodiment has been included in a cam assembly which is carried by the same shaft that carries the transfer cam assembly but which is independently driven. The latter embodiment is disclosed in two variations, in one of which the operating cycle of the printing cam may occur almost entirely after the transfer cam has reached the arrest position, which is true of the embodiment employing the two driving shafts, and in the other of which the cycle of the printing cam may lag behind the transfer cam by only a relatively small fraction of a cyclic interval.

Certain of the features of the invention disclosed in the present disclosure and in the patent of which the present disclosure is a division, but not claimed herein or in said patent from which the present application is divided, are also disclosed and are claimed in Patent No. 2,247,408, granted July 1, 1941, to Albert H. Reiber; Patent No. 2,248,097, granted July 8, 1941, to Edward S. Larson; Patent No. 2,230,463, granted February 4, 1941, to Carl A. Levin; Patent No. 2,242,272, granted May 20, 1941, to Carl W. Swan; and Patent No. 2,224,546, granted December 10, 1940, to Herman Lotterman.

For a complete understanding of the present invention reference may be had to the following detailed description to be interpreted in the light of the accompanying drawing wherein the single figure, when considered in conjunction with the disclosure of the afore-mentioned patent to Berthel F. Madsen and of which the present application is a division, shows a schematic elevational view of a portion of a printing telegraph apparatus and illustrates particularly the details of the mechanism for effecting shift and unshift functional operations of the apparatus.

Referring to the drawing, it will be observed, that the shaft 11, which may correspond to shaft 317 in Fig. 4 of the afore-mentioned patent to Berthel F. Madsen supports a cam sleeve 12 which may be clutch driven as in Fig. 4 thereof and which has secured thereto type wheel elevating cam 13 and printing cam 14. A first-class lever 15 mounted on a pivot stud 16 carries a cam follower roller 17 for engagement with the type wheel elevating cam 13. Also pivoted on the stud 16 is a third-class lever 18 which is articulated to type wheel supporting frame 19 which is in turn slideable on a stud 20, there being a slot 21 formed in the type wheel supporting frame for receiving the stud 20. The type wheel supporting frame 19 is normally urged downwardly by a spring 22, thereby to carry a type wheel designated generally by the numeral 23 down out of association with a platen, not shown, but positioned similarly to the platen in the afore-mentioned patent to Berthel F. Madsen of which the present application is a division.

Positioned for cooperation with the type wheel 23 is a printing hammer 24 which is articulated to a printing bail 25. The printing bail 25 is

pivoted intermediate its ends on a stud 26 and is normally urged to rock about the stud 26 in a clockwise direction by a contractile spring 27. Adjacent the lower end of the printing bail 25, there is formed thereon a projection 28 which is adapted to engage the periphery of the print cam 14. Above the projection 28, the bail 25 is provided with a projection 29 which abuts the end of a spring pressed plunger 30 when bail 25 is in normal position. Plunger 30 operates as a yieldable stop which opposes spring 27 when bail 25 is in rest position, and holds the free end of the print hammer 24 out of the path of the type pallet of type wheel 23. In the rest condition 15 of the printing apparatus there is a gap between projection 28 on the printing bail 25 and the periphery of print cam 14. This gap permits bail 25 and print hammer 24 to overtravel sufficiently to actuate a type pallet. Cam 14 is rotatable in 20 a clockwise direction and as it rotates it imparts counterclockwise movement to the bail 25 thus retracting the print hammer 24 from the normal position and distending the spring 27. The drop-off of cam 14 from maximum to minimum radius 25 is extremely sharp and when projection 28 of bail 25 encounters this drop-off, bail 25 is released and spring 27 rocks bail 25 sharply in clockwise direction. Due to the inertia of bail 25 and print hammer 24, they overtravel to operate a selected 30 type pallet and effect printing therefrom. In overtraveling, bail 25 depresses plunger 30 which in turn compresses its spring slightly. As soon as the energy of bail 25 and print hammer 24 has been expended, plunger 30 restores bail 25 to normal position by rocking it slightly in a counterclockwise direction.

Print bail 25 is provided with a depending finger 31 in the path of overtravel of which is disposed the upper end of a latch 32. The latch 40 32 is pivoted on a pin 33 and is urged to rock in a clockwise direction by a spring 34. Latch 32 has a shoulder 35 formed on it for engagement with a laterally extending arm 36 formed integrally with the first-class lever 15 to latch the lever 15 in its counterclockwise position in the interval between the camming of the lever to that position and the printing interval or the interval when the printing bail 25 is actuated by its spring 27 upon engagement of the projection 50 28 of the bail 25 with the low portion of cam 14. First-class lever 15 is normally urged to rock about the stud 16 by a spring 37 so that upon release of the laterally extending arm 36 by shoulder 35 on lever 32, under the action of 55 the printing bail 25, the first-class lever 15 will be rocked clockwise about its stud 16. It will be apparent from this that substantially at the instant that printing is effected latch 32 is tripped and spring 22 is enabled to restore the type wheel 60 lifting frame 19 to its lowermost position immediately and without supervisory control by the cam 13.

The third-class lever 18, intermediate its ends, pivotally supports a latch 45 which is spring 65 biased in a counterclockwise direction. Latch 45 is provided with an undercut portion engageable by the right-hand end of the first-class lever 15. When latch 45 is engaging the end of lever 15 and the lever is rocked in a counterclockwise direction by cam 13, the third-class lever 18 is rocked in clockwise direction through the same angular distance as lever 15 to effect the elevation of the type wheel 23 to its uppermost position. When, however, latch 45 is rocked in a clockwise 70 direction to disengage it from the end of the

lever 15, the lever 15 may rock in counterclockwise direction without imparting rotation to lever 18 until lever 15 comes into engagement with an abutment pin 46 carried by lever 18. After coming into engagement with pin 46 lever 15 will impart rotation in counterclockwise direction to third-class lever 18, but the distance through which lever 18 will be rocked will be less than the distance through which lever 15 was rocked, the difference resulting from the lost motion which lever 15 undergoes in order to come into engagement with pin 46 and, therefore, the type wheel 23 will be elevated a lesser distance than it is when latch 45 is engaging lever 15, the type wheel thus being elevated to position for printing from the upper row of type pallets.

The case shift control mechanism for controlling the effectiveness of first-class lever 15 in elevating the type wheel 23 to its printing position is controlled in a manner similar to that disclosed in the afore-mentioned patent to Berthel F. Madsen, in that shift and unshift function bars 47 and 48, respectively, control the height to which the type wheel 23 will be elevated to effect printing in upper or lower case characters. Function levers 49 and 50 are pivotally mounted so as to be capable of operation independently and individually by the function bars 47 and 48, respectively. The levers 49 and 50 are pivoted at 51 and carry projections 52 and 53, respectively, which engage a pivoted lever 54 to rock it to either of its adjusted positions. The projections 52 and 53 engage the left edge of the lever 54 and serve to rock it to either of its positions where it will be locked by a spring biased detent 55 having two notches 56 and 57 for engagement alternately with the upper pointed end of the lever 54. The lower end of the lever 54 has a laterally extending projection 58 which is adapted to engage the upwardly extending end of the latch 45 when the lever 54 is moved to its counterclockwise position (the opposite position to that shown). When the lever 54 is rocked to its counterclockwise position, the projection 58 strikes the latch 45 and disengages it from the end of first-class lever 15 and when the cam 13 rocks lever 15, the first portion of its rocking movement will be idle until the right end of lever 15 engages the pin 46 whereupon the lever 15 and the third-class lever 18 will then move as a unit. If, however, the levers 49 and 50 are set in the position shown and locked in that position by the detent 55 engaging the upward end of the lever 54 and holding it in the position shown, the lever 15 upon being rocked by the cam 13 will immediately carry the third-class lever 18 with it due to the interconnection of the lever 18 and the lever 15 by means of the latch 45.

In the operation of the apparatus, the receipt of a shift signal will cause the shift function bar 48 to be moved to the right, thereby to rock the function lever 50 to the position shown. When the function lever 50 is rocked to the position shown, it will rock lever 54 to its clockwise position as shown, and first-class lever 15 in following the contour of cam 13 will engage the sloping face of latch 45 to move latch 45 in a clockwise direction against the action of its biasing spring until the lever 15 has moved its right end under the latching portion of latch 45 as shown in the drawing. Upon the receipt of a character indicating signal, the proper type pallet in the type wheel 23 will be selected in the manner described in the afore-mentioned patent to Berthel F. Madsen referred to hereinbefore and the type

wheel will be elevated to its highest position due to the action of cam 13 on roller 17 moving the first-class lever 15 and the third-class lever 18 as a unit, thereby to carry the type wheel to its uppermost position.

Upon the receipt of a signal indicating unshift, the unshift function bar 47 will be shifted to the right as described in the hereinbefore mentioned patent to Berthel F. Madsen and function lever 49 will therefore be rocked to the right or in a counterclockwise direction by the function bar 47 to move lever 54 out of the notch 56 and into the notch 57. In moving from the position shown to the counterclockwise position, or the position where the upward end thereof engages in the notch 57, lever 54 will rock function lever 50 in a clockwise direction, thus resetting lever 50 for the receipt of a shift signal. Similarly, when the function lever 50 is selected, its projection 53 rocks latching lever 54 in a clockwise direction thereby causing the latch lever 43 to engage the projection 52 of function lever 49 to return lever 49 to its original position in readiness for the receipt of an unshift signal. Lever 54 will also engage latch 45 and unlatch the lever 18 from the lever 15 so that when the high portion of cam 13 engages cam follower roller 17, the first portion of the movement of first-class lever 15 will be idle until the right end of lever 15 engages the pin 46 whereupon the type wheel supporting frame 19 will be moved against the action of spring 22 to carry the type wheel 23 to the lower of its two elevated positions.

It should be noted that while spring 37 normally urges the lever 15 to rock in a clockwise direction to hold the cam follower roller 17 in engagement with the surface contour of cam 13, that the roller 17 does not always engage the cam 13, but that lever 15 upon being rocked to its farthest counterclockwise position by cam 13 will be latched in that position due to the action of latch 32 engaging its shoulder 35 with the laterally extending arm 36 on lever 15. By this means, the type wheel 23 will be held in its uppermost position until the printing bail 25 is actuated by its spring 27 upon alignment of projection 28 on bail 25 with the drop-off of cam 14. Thus immediately after printing is effected by the print hammer 24, the portion or finger 31 of printing bail 25 will strike the upper extending end of latch 32 and disengage the shoulder 35 of latch 32 from the laterally extending arm 36 on lever 15 thereby to permit the spring 37 to move the cam follower roller 17 into engagement with the surface of cam 13.

Although a specific embodiment of the invention has been described hereinbefore it will be understood that numerous modifications and adaptations thereof may be made without departing from the invention which is to be limited only by the scope of the appended claims.

What is claimed is:

1. In a printing telegraph apparatus, a rotatable type wheel, a shaft upon which said type wheel is slidably mounted, a frame for supporting said type wheel, means for lifting said frame before each printing operation and for lowering said frame after each printing operation, means associated with said frame having a fixed element and a movable element engageable by said lifting means to move said frame to different levels dependent on the element engaged, pivotally mounted means, means controlling the position of said pivotally mounted means where-

by said lifting means will engage either said movable element or said fixed element to elevate said frame to its different levels, and means for selectively operating said controlling means.

2. In a printing telegraph apparatus, a rotatable type wheel, a shaft upon which said type wheel is slidably mounted, a frame for supporting said type wheel, a power actuated lever for lifting said frame before each printing operation and for lowering said frame after each printing operation, a lever articulated to said frame and having a movable element and a fixed element selectively engageable by said power actuated lever for elevating said frame to different levels dependent on the element engaged, means operable under predetermined circumstances for enabling the engagement of said movable element by said power actuated lever and under other predetermined circumstances for moving said movable element out of position with respect to said power actuated lever whereby said power actuated lever engages said fixed element, and means for selectively operating said means.

3. In a printing telegraph apparatus, a rotatable type wheel, a shaft upon which said type wheel is slidably positioned, a frame for supporting said type wheel, a pivoted lever for elevating said frame, a power actuated lever, a latch on said pivoted lever for latching said lever to the power actuated lever to enable said power actuated lever to raise said frame to a predetermined level, selectively actuatable means for rendering said latch effective or ineffective, and means on said first mentioned lever for engagement by said power actuated lever when said latch is rendered ineffective to enable said power actuated lever to raise said frame to another predetermined level.

4. In a printing telegraph apparatus, a rotatable type wheel, a shaft upon which said type wheel is slidable, a frame for supporting said type wheel, a lever articulated to said frame for moving said type wheel to different positions, a primary lever for actuating said articulated lever, a latch for connecting said levers to enable said primary lever to move said articulated lever to a predetermined position, selectively operated means for enabling the operation of said latch and for disabling said latch, and fixed means on said articulated lever engageable by the primary lever upon the disablement of said latch to enable said primary lever to move said articulated lever to another predetermined position.

5. In a printing telegraph apparatus, a rotatable type wheel, a shaft upon which said type wheel is slidable, a frame for supporting said type wheel, a lever articulated to said frame for moving said type wheel to different typing levels, a primary lever for actuating said articulated lever, a latch for connecting the first and second levers to enable said primary lever to move said articulated lever to a predetermined position, selectively operable means for rendering said latch effective and for disabling said latch, fixed means on said articulated lever engageable by said primary lever upon disablement of said latch to enable said primary lever to move said articulated lever to another predetermined position, and a pair of unidirectionally movable levers for controlling the operation of said selectively operable means.

6. In a printing telegraph apparatus, a rotatable type wheel, a shaft upon which said type wheel is slidable, a frame for supporting said

type wheel, a lever articulated to said frame for moving said type wheel to different typing levels, a primary lever for actuating said articulated lever, a latch for connecting said levers to enable said primary lever to move said articulated lever to a predetermined position, selectively operable means for rendering said latch effective or for disabling said latch, fixed means on said articulated lever engageable by said primary lever upon the disablement of said latch to enable said primary lever to move said articulated lever to another predetermined position, and a pair of function levers alternately operable for controlling the operation of said selectively operable means.

7. In a printing telegraph apparatus, a rotatable type wheel, a shaft upon which said type wheel is slidable, a frame for supporting said type wheel, a lever articulated to said frame for moving said type wheel to different typing levels, a primary lever for actuating said articulated lever, a latch for connecting said levers for enabling said primary lever to move said articulated lever to a predetermined position, a pair of function control means, means operated by said control means for rendering said latch effective or for disabling said latch, and fixed means on said articulated lever engageable by said primary lever upon the disablement of said latch to move said articulated lever to another predetermined position.

8. In a printing telegraph apparatus, a rotatable type wheel, a shaft upon which said type wheel is slidable, a frame for supporting said type wheel, means for elevating said type wheel supporting frame to either of two positions including a lever assembly including two levers having a common pivot and interconnectable in either of two different relative positions to enable said lever assembly to move said type wheel supporting frame to different typing levels, and means to effect the selective interconnection of said levers.

9. In a printing telegraph apparatus, a rotatable type wheel, a shaft upon which said type wheel is slidable, a frame for supporting said type wheel, means for elevating said type wheel supporting frame to either of two positions comprising a lever assembly including two levers having a common pivot and interconnectable in either of two different relative positions, one of said levers being articulated to said frame, a pair of function bars, a function bar controlled latch for interconnecting the levers in one of said relative positions, a pin for interconnecting the levers in the other of said relative positions, and means selectively operated for operating said function bars to render said latch effective or ineffective whereby the interconnection will either be through said latch or said pin.

10. In a printing telegraph apparatus, a rotatable type wheel, a shaft upon which said type wheel is slidable, a frame for supporting said type wheel, and means for elevating said type wheel supporting frame to either of two positions comprising a lever assembly including two levers having a common pivot and interconnectable in either of two different relative positions, one of said levers being articulated to said frame, a latch on one of said two levers relatively engageable with the other of said two levers for interconnecting them in one of said relative positions, and a pin on the first mentioned one of said levers for engagement by the other of said

two levers to interconnect the two levers in the other of said two relative positions.

11. In a printing telegraph apparatus, a type member, a supporting means therefor, means for lifting said supporting means, means associated with said supporting means having a fixed element and a movable element against either of which said lifting means is engageable to raise said supporting means to different levels dependent on the element engaged, means to determine the particular element with which said lifting means will be in engagement whereby said supporting means is raised to predetermined typing levels, and selectively operated means for controlling the position of said determining means. 15

12. In a case shift device, a type carrying member movable to either of two positions, means for elevating said type carrying member, power means for operating said elevating means, a fixed and a movable element associated with said elevating means, means for determining whether said power means will engage said fixed element or said movable element to move said elevating means to different predetermined positions, and means to operate said determining means selectively to render said power means effective with said fixed element or said movable element.

BERTHEL F. MADSEN.
